UNITED STATES PATENT OFFICE

RALPH J. TEETOR, OF CADILLAC, MICHIGAN, ASSIGNOR TO THE COLORADO FUEL & IRON COMPANY, OF DENVER, COLORADO, A CORPORATION OF COLORADO

ROADWAY GUARD

Application filed February 18, 1928, Serial No. 255,276. Renewed March 17, 1933.

The present invention relates to roadway guards; and its object is, generally, to provide an improved structure to prevent vehicles from running off the side of the roadway.

This and any other and more specific objects hereinafter appearing are attained by, and the invention finds preferable embodiment in, the structure hereinafter particularly described in the body of this specification and illustrated by the accompanying drawing, in which:

Figure 1 is a plan view of a roadway and of a guard disposed at one side thereof;

Figure 2 is a view in perspective of a portion of the same;

Figure 3 is a side elevation of one of the vertical supports comprised in said structure and cables (with connecting devices) connected thereto; and

Figure 4 is a top plan view of portions of said cables and their connecting device.

In the embodiment of the invention illustrated by said drawing, my roadway guard is positioned adjacent the convex outer side 1 of the roadway 2 and comprises a plurality of spaced vertical supports, the posts 3, 4, the extreme posts 3 having desirably guy rods or cables 5 secured thereto at 6 and anchored to short posts 7 driven into the ground.

A flexible main cable 8 is (or a pair thereof vertically spaced apart as shown are) connected at their ends 9 to these supports 3 in any suitable manner. Flexible cables 10 are connected at one of their ends to the intermediate supports 4 and at their other ends to the main cables 8 respectively, and at spaced distances apart corresponding to the spacing apart of the supports. Eye bolts 11 are looped through a link of the connecting means 10 and adjustably held on the supports by nuts 22.

These cables 10 hold the main cables 8 more or less tautly in suspended position between the extreme supports 3, 3, and nevertheless permit the same to be flexed within limits (when struck by a passing vehicle) from the position seen in Figure 1 in which they normally extend. It will be seen that

such flexing under the impact of the vehicle may involve the entire length of the main cables between their extreme supports 3, 3.

The cables 10, 10 are desirably connected between the main cables and the supports 4 by flexible cables 13 whose lower ends are anchored to said supports near the ground. In order that a vehicle striking the main cables may slide along the same without striking any projection carried thereby, the cables 10 are connected to the main cables 8 at points 16, remote from the roadway, i. e., on that side of the main cables which is opposite the roadway.

To effect this end, connecting devices are illustrated in Figures 3 and 4, comprising a U-shaped member 18 embracing the strand 16 of the main cable which is (at that point in its length) nearer the support 4 and remote from the roadway. This member 18 has bolts 20 connecting it to the outermost link of the cable 10.

The nuts 22 on the eye bolts 11 provide means to selectively vary the tension of one or both of the cables 8.

The invention being intended to be pointed out in the claims, is not to be limited to or by details of construction of the particular embodiment thereof illustrated by the drawing or hereinbefore described.

I claim:

1. A roadway guard rail comprising: a plurality of spaced vertical supports adjacent the side of the roadway; a plurality of vertically spaced main cables connected to the extreme supports; cables connected at one of their ends to the intermediate supports respectively and at their other ends to the main cables respectively at spaced distances apart; cables connected to the second-mentioned cables intermediate the supports and the main cables and having their lower ends anchored in fixed relation to the ground.

2. A roadway guard rail comprising: a plurality of spaced vertical supports adjacent the side of the roadway; a main cable connected to the extreme supports and comprising intertwined strands; cables connected at one of their ends to the interme-

- diate supports respectively and at their other ends to the main cable at spaced distances apart and holding the main cable in suspended position; devices for connecting 5 the second-mentioned cables to the main cable, each of said devices having a strand embracing only a portion of the main cable which is adjacent the supporting intermediate support.
- 10 3. A highway guard fence comprising a series of posts, cables projecting forwardly from each post, a flexible barrier supported at the outer ends of the cables projecting from the posts and a connection between 15 the cables of each post, separate from the barrier.
4. A highway guard fence comprising a series of posts, cables projecting forwardly from each post, a flexible barrier supported 20 at the outer ends of the cables projecting from the posts, and a flexible connection between the cables of each post, separate from the barrier and anchored to the post.
5. A highway guard fence comprising a 25 series of posts, cables projecting forwardly from each post, a flexible barrier supported at the outer ends of the cables projecting from the posts, and a flexible connection between the cables of each post, separate 30 from the barrier and anchored at a point below the cables.
6. A highway guard fence comprising a series of posts, cables projecting forwardly from each post, a flexible barrier supported 35 at the outer ends of the cables projecting from the posts, a connection between the cables of each post and between one of the cables and the post, said connection being separate from the barrier.
- 40 In testimony whereof I have hereunto set my hand at Cadillac, Michigan, this 14th day of February, 1928.

RALPH J. TEETOR.
